ABSTRACT

A paper envelope of conventional form comprising a rectangular front face, inwardly folded end flaps, an upwardly folded bottom flap, and a downwardly folded top or closure flap, characterized by a cutout portion in one of the flaps, preferably the bottom flap, which provides a printing area on the front face which is of uniform three thicknesses of paper throughout such area and permits printing of a return address in such area without resort to the make-ready printing procedure.

NOTCHED FLAP ENVELOPE

BACKGROUND OF THE INVENTION

In the marketing of envelopes for ultimate use by a consumer, a practice now exists in which the envelope is marketed with the consumer's return address information printed in the upper left corner of the front face of the envelope. The consumer generally prefers that such address be of the same size, that is, occupy the same area on the envelopes, regardless of envelope size. Moreover, the uniform size of return address effects economics to the consumer since only one type setup is required for all. While a myriad of envelope constructions have been proposed or used, a widely accepted construction comprises a rectangular front face or wall, a pair of inwardly folded generally triangular end flaps, a bottom generally isosceles triangular shaped upwardly folded bottom flap, cemented along its edges to the end flaps, and a top generally rectangular top or closure flap adapted to be glued along its longitudinal edge to the bottom and end flaps when the envelope is sealed. The corners of the end flaps are usually rounded, the bottom flap may have a straight portion joining its side edges and the top flap may depart somewhat from a true rectangle. Regardless of the variations just referred to, the top flap when closed overlies portions of the bottom flap and end flaps and produces an area in the upper corners of the front face which are of three thicknesses of paper and a fourth thickness where the top flap overlies the bottom flap. If a portion of a return address on the front face of the envelope, conventionally in the upper left corner, is printed in the area of four thicknesses occurring when the flap is closed as is conventional, this creates printing problems since the printing type must now be impressed upon an area partly of three thicknesses and another area of four thicknesses. The same problem exists regardless of the number of paper layers whenever the envelope construction requires printing on an area of nonuniform thickness. Since this would result in defective printing it has been the practice to employ a make-ready procedure which involves the use of a shim or shims to make the area referred to of uniform thickness which is a time-consuming procedure and adds to the cost of printing.

SUMMARY OF THE INVENTION

The invention eliminates the make-ready procedure for envelopes having the same size return address area even though the envelopes are of different sizes because when the invention is applied to envelopes of various sizes, which have a uniform make-ready area, the need for altering the make-ready area on the printing press is eliminated. By the practice of the invention the nonuniform thickness of paper in the return address area is eliminated by prefabricating the envelope blanks with a cutout portion in one of the flaps, preferable the bottom flap of an envelope having four thicknesses of paper in the return address area. The elimination of the make-ready procedure for envelopes of different sizes results in a considerable saving in the printing costs.

It is thus a principal object of the invention to provide a method for the elimination of the nonuniform thickness in the return address printing area of conventional envelopes of different sizes which have a uniform size return address printing area.

The invention is illustrated by its application to an envelope having four thicknesses of paper; however, it can be applied to provide a uniform thickness return address printing area irrespective of the envelope thicknesses.

BRIEF DESCRIPTION OF THE DRAWING

FIG. 1 is a rear elevation of the subject invention prior to sealing the various flaps.

FIG. 2 is a like elevation with the end flaps sealed to the bottom flap, and

FIG. 3 is a plan view of the back of three envelopes of different widths and lengths with the envelopes of diminishing dimensions superimposed on the larger envelopes.

DESCRIPTION OF PREFERRED EMBODIMENTS

Referring now to the drawing, and first to FIG. 1, envelope 10 comprises a rectangular front wall 12, end flaps 14, 16, bottom flap 18 and top closure flap 20, all of conventional form, except that bottom flap 18 is provided with a cutout 22. End flaps 14 and 16 are provided with a gummed material 24 on their outside surfaces adjacent to their edges for gluing the bottom flap 18 to them after they are folded inwardly, and the top closure flap is provided with like material 24 for sealing it to the other flaps after the correspondence or other enclosure has been inserted into the envelope. FIG. 2 illustrates the envelope with the end flaps glued to the bottom flap and in condition to receive its enclosure. FIG. 3 shows envelopes of different sizes conventionally made with the same size return address printing area.

Referring to FIG. 2, it will be seen that when the flap 20 is folded before printing in the return address area 26 there will be a uniform printing area of three thicknesses due to the fact that cutout 22 has been cut in bottom flap 18.

Reference is now made to FIG. 3 showing conventional envelopes A, B and C of different sizes in which a uniform return address printing area 26 is used for different size envelopes. It will be noted that although the cutout 22 may vary slightly for different size envelopes, it is always adequate to clear the return address area 26 so that all sections of area 26 are of uniform thickness. Different size dies are used to make the cutout for different size envelopes.

The cutout 22 is preferably formed during the fabrication of the envelope blank and requires only a slight modification to a die shearing edge to conform to the desired shape of the cutout. It will be apparent, however, that envelope blanks prefabricated without the cutout, may later be modified by a suitable cutting die, or otherwise to make the cutout.

It is to be understood that this invention is not limited to the exact methods and embodiments shown and described, which are merely by way of illustration and not limitation, as various other methods, forms and modifications will be apparent to those skilled in the art. For example, a uniform thickness return address printing area could be achieved by altering the dimensions of bottom flap 18 and cutting out a portion of either top flap 20 or left end flap 14. Also, for an envelope of three thicknesses in which the back flap 18 is of one thickness and the same size as front flap 12, a uniform two thickness area could be formed by cutting out a notch in either the sealing flap 20 or the one piece back flap 18. Accordingly, it is intended that the appended claims cover all such changes and modifications.

What is claimed is:

1. In a conventional envelope of sheet material of the type forming a first front panel having a generally rectangular return address area at its upper left corner, an end flap forming a second panel having an area contiguous and coextensive with said return address area, whereby the first and second panels provide a uniform thickness of two sheets of material throughout said return address area, and a bottom flap, forming a third panel having a portion in its upper left corner, as viewed through the front face of the envelope, adjacent said area of said second panel, said third panel forming a third thickness area of material, the improvement, in combination, comprising:
a cutout in said bottom flap at the locus of said area of said second panel, for increasing the return address area of uniform two thicknesses, to permit uniform impression of printed return address information throughout the return address area, and an increased by said cutout, without use of a shim beneath said second area, and
a top flap having a portion contiguous and coextensive with said two thicknesses, forming three uniform thicknesses of material in said return address area when the top flap is closed.
2. An envelope in accordance with claim 1 wherein:
said top flap, when closed, overlies and conceals said cutout.
3. An envelope in accordance with claim 1 wherein:

said top flap is generally rectangular.

4. An envelope in accordance with claim 1 wherein:

said bottom flap is generally isosceles triangle in shape with
a generally flat apex, said cutout being disposed adjacent
one end of said apex.
